UNITED STATES PATENT OFFICE.

JACOB S. LOWE, OF GENEVA, OHIO.

BLACKBOARD-ERASER.

SPECIFICATION forming part of Letters Patent No. 366,674, dated July 19, 1887.

Application filed June 1, 1886. Serial No. 203,744. (Model.)

To all whom it may concern:

Be it known that I, JACOB S. LOWE, of Geneva, in the county of Ashtabula and State of Ohio, have invented a certain new and Improved Blackboard Eraser; and I do hereby declare that the following is a full, clear, and complete description thereof.

The nature of my invention relates to the combination of material and construction of the said article, which consists in making the face of felt at the ends, while the central or intermediate portion, of fustian of any suitable surface, form, or configuration, is folded or lapped over a filling, and then glued or otherwise fastened to the handle with polishing-felt attached to the ends by any suitable device for the purpose designed.

To enable others to fully understand the nature of said invention that it may be made and used, reference will be had to the following specification and to the annexed drawings, making part of the same, in which—

Figure 1 is a side view of the said eraser. Fig. 2 is an end view; Fig. 3, a longitudinal vertical section; Fig. 4, a transverse vertical section in direction of the line x x , Fig. 1. Fig. 5 is a face view.

Like letters designate like parts in the drawings and specification.

The handle A, Figs 1 and 2, is preferably made of wood, and of such shape best adapted in use to the hand, and having an extension, B, to which is attached the erasing material for the face of the eraser. The central part or section, C, Figs. 3, 4, and 5, is composed of fustian, its face being of any suitable form or configuration for the purpose designed. This fustian is lapped over an interior packing, D, Figs. 3 and 4, consisting of laminated pasteboard or its equivalent, which forms a cushion, and also raises up the face C, of fustian, to the same plane with the felt ends E F, as seen in the drawings. The central section of fustian G, Figs 3 and 4, or its equivalent, after being so lapped over the filling D as to inclose it, is then secured to the extension B by being cemented thereto or otherwise

properly attached. The felt ends E and F are then fastened to said extension in close contact with the central section, as seen in Fig. 5.

The face B' of the extension may be either flat or curved longitudinally, and as the felt is usually thicker than the fustian, a central or intermediate section may form a projection from the face B' of the extension B, and the fustian laid over it so as to be in the same plane with the felt ends.

In the use of erasers the friction is mostly at the ends of the instrument; and from the nature of my improvement it has a decided advantage in durability over those ordinarily in use.

Strips or pieces (preferably) of polishing-felt of suitable thickness cover over the ends of the extension B, as shown in the drawings.

Felt, being thicker and more compact, will wear much longer than fustian or corduroy when subjected to the same amount of practical use. The relative value of wear may be formulated as felt, 2; fustian or corduroy, 1. The fustian, being in the central part of the eraser, is subjected to less friction than at the ends; hence there is a uniform wear of the entire face at less cost with increased durability, while the combination of fustian with felt, as described, (thereby uniting the erasing qualities of each,) will together form such an erasing-surface as will remove all marks and traces of any crayon now in general use, leaving the board clean and free from the "crayon smudge" so common on school-room blackboards.

An addition to the advantages derived from the use of my improvement is that in the surface of my eraser the crayon dust does not pack as it will in an eraser composed entirely of felt, thereby rendering it easy to be kept clean and free from dust.

In thus combining fustian and felt in the same eraser, as described, and for the purposes already set forth, I retain the good qualities of each and avoid their objection-

able properties, separately considered, while at the same time I produce a better article at less cost, as fustian is less expensive than felt.

What I claim as my invention, and desire 5 to secure by Letters Patent, is—

In a blackboard eraser, the combination of fustian with polishing-felt forming the erasing-surface, arranged, as shown, in connection with the interior packing of pasteboard,

and the handle provided with an extension, to B, substantially as and for the purpose set forth.

In testimony whereof I affix my signature in presence of two witnesses.

JACOB S. LOWE.
